UNITED STATES PATENT OFFICE.

MORRIS GOLDSSTONE, OF BROOKLYN, NEW YORK.

WINDOW-CLEANER.

1,353,741.

Specification of Letters Patent. Patented Sept. 21, 1920.

Application filed February 7, 1920. Serial No. 356,923.

To all whom it may concern:

Be it known that I, MORRIS GOLDSSTONE, a citizen of Russia, and a resident of the city of New York, borough of Brooklyn, in the county of Kings and State of New York, have invented a new and Improved Window-Cleaner, of which the following is a full, clear, and exact description.

This invention relates to cleaning machines, and more particularly to a window cleaner.

The primary object of the invention is to provide a mechanically-driven window-cleaning machine which cleans windows or other surfaces at a rapid rate, and which may be used to clean windows or other surfaces without employing ladders for gaining access to windows located high off of the floor, or for cleaning large show and store windows where considerable surface is exposed and where considerable manual labor is necessarily employed.

It is a purpose to provide an electrically-driven window-cleaning machine, positive and dependable in operation, light in weight, and having such simplified construction and operation as will render the cleaner capable of being operated by most any person who is able to manipulate the machine.

It is a further purpose to provide a cleaning machine incorporating a cleaning surface which may be renewed from time to time, and which also employs an adjustable handle for manipulating the window cleaner and moving it over the surface to be cleaned.

With the above principal objects, and others, in view the invention has relation to the cleaning machine, one form of which is described in the following specification and illustrated in the accompanying drawings; while several modifications in design and structure are covered in the appended claims.

Figure 1 in the drawings shows a window-cleaning machine in side elevation with the cleaning wheel in section to portray the operative parts thereof;

Fig. 2 illustrates a rear elevation of the window-cleaning machine; and

Fig. 3 illustrates a fragmentary sectional view taken through the handle portion of the cleaning machine to illustrate the end of the handle as attached to the machine.

A cleaning machine constructed in ac-

cordance with the purpose of my invention employs a cleaning wheel having a clamp associated therewith for holding a cleaning cloth in such a way that the cloth may be periodically changed during cleaning operations. The cleaning wheel is driven by an electric motor, and an adjustable handle is attached to the frame of the motor for moving the cleaning wheel back and forth over the surface to be washed.

A more detailed disclosure of my invention shows a motor casing 4, having a post 5 integral therewith and projecting from one end. An electric motor 6 is shown in dotted lines in the drawings, contained in the casing 4 and having a drive shaft 7.

A cleaning wheel 10 is constructed preferably of laminated material, as, for example, laminated wood. This construction provides a cleaning wheel of great strength and light in weight. A flange 11 is fixed to the cleaning wheel and is mounted on the drive shaft 7 to turn with and be driven by the shaft. A rubber covering 12 is applied to the working face of the cleaning wheel and excludes water from the veneered construction of the wheel, and provides a frictional gripping surface to hold a cleaning cloth, as later seen. It is obvious that any suitable form or structure of wheel 10 may be employed.

A flange 14 is fixed on the drive shaft 7 and is exteriorly threaded to receive an interiorly-threaded cloth clamping ring 15. The clamp 15 is, in fact, similar to a flange, and has a clamping face 16 which engages the face of the cleaning wheel. By grasping the cleaning wheel 10 and holding it in fixed position, the clamp ring 15 may be rotated to move the clamping face 16 away from the face of the cleaning wheel 10. This action is effected through the threaded connection existing between the flange 14 and cloth clamp ring 15; and as the member 15 is rotated in the proper direction it is caused to travel away from the cleaning wheel.

A cleaning cloth 13 is applied to the outer working face of the cleaning wheel 10 in the manner shown in Fig. 1, where the cloth is stretched over the face of the wheel, and the edges thereof brought around the rim of the wheel and passed under the clamping face 16 between the cleaning wheel 10 and

the cloth clamp ring 15. The member 15 is then rotated to move it back in engagement with the cloth 13 and, thus, clamp the cloth to the cleaning wheel in firm and substantial relation.

A handle socket 18 is provided having ears 19 made on one end. A lug 17 is integrally formed on the handle socket 18 and acts as a stop to limit the motion of the handle when mounted, as shown in Fig. 1. A pin 20 is passed through the ears 19 and through a bearing hole made in the post 5, to pivotally carry the handle socket 18 upon the motor casing 4. The handle socket 18 is, therefore, free to pivot upon the post 5.

A handle 22 is inserted in the socket 18 and rotatably confined therein. A spring 23 is interposed between the base of the socket and the end of the handle 22 by turning down each end of the spring 23 and inserting the ends into a recess formed in the end of the handle and in the base of the socket. In this manner the spring 23 acts to restrain the rotation of the handle 22 in the socket 18. The handle is permitted to undergo swiveling motion, but the spring acts as a positive elastic restraint to return the handle socket to its normal centralized position. The handle 22 is provided with slotted openings, and pins 24 are fixed in the handle socket and inserted in the slotted openings of the handle to confine the handle in the socket, but yet will allow the handle a degree of freedom in rotation therein, as just described. The handle is preferably tubular in form so that the electric transmission cord 25 may be contained in the handle for transmitting the electric power to the motor 6 for driving the machine. A switch 26 of any suitable design may be carried on the handle for stopping and starting the motor.

Bolt keepers 28 and 29 are fixed to the post 5, the first keeper being fixed to the side thereof and the other keeper fixed to the end of the post. Each keeper has a slotted cut therein to provide a receptacle or guide between the keeper and the surface of the post. A guide plate 30 is fixed on the handle socket and slidably retains a bolt 31. The lower end of the bolt 31 may be turned up, as shown in the drawings, to provide a hand catch for pushing the bolt in and out of engagement with the keepers. The upper end of the bolt 31 is provided with a tongue 32 which may be struck from the bolt 31 to form an integral structure therewith. This formation of the upper end of the bolt provides the inner locked portion 33 which slides into position between the keeper and the post, and the outer locked tongue 32, which engages the outer portion of the keeper. In this manner the bolt 31 is made to engage with the keeper 29 to hold the cleaning machine in one fixed position, while

the machine may be adjusted to a new position by sliding the bolt 31 out of engagement with the keeper 29 and rotating the machine about the pin 20 until the bolt 31 will engage the keeper 28. In this way it is seen how the working face of the cleaning wheel 10 may be held in either a parallel or perpendicular relation to the handle 22. These two positions of the machine are shown in Fig. 3, where the post 5 of the machine is disposed perpendicular to the handle 22, in dotted lines, and in each position the locking means provided is positive and dependable, such that the entire structure comprises a rigid unitary assembly. The bolt is made of flexible spring steel and yields slightly to the movement of the handle and pressure by the operator.

In the operation of the machine a suitable cleaning cloth 13 is applied to the working face of the cleaning wheel 10 and clamped in position by the cloth clamp ring 15, as hereinbefore described. If the window, or surface to be cleaned, is high above the floor, then the handle 22 should be adjusted in fixed relation parallel to the working face of the wheel 10, as shown in Fig. 1, in order that the operator may move the cleaning wheel 10 back and forth and up and down over the surface. But, however, if the window is, perhaps, on a level with the operator the adjustment of the machine may be made such that the handle is set perpendicularly to the working face of the wheel, so that the surface may be cleaned directly in front of the operator. The switch 26 is located at any convenient and accessible position on the handle, so that the machine may be stopped and started at will. In moving the cleaning wheel back and forth across surfaces to be cleaned, the operator will tightly grasp the handle 22, which causes a slight swiveling motion of the machine about the handle. This action is effected through the pin 24 and slot arrangement, as shown in detail in Fig. 3, and the spring 23 acts to assist the return of the machine to its original position. In this manner the operation of the machine is flexible and universal in motion to permit the cleaning wheel to accommodate itself to the relative positions of the window to be cleaned and the operator handling the machine.

A cleaning cloth 13 of any suitable thickness may be employed, but it is preferable to use a cloth of considerable thickness, and absorbent, in order that a considerable quantity of water may be held by the cloth for wetting the surface to be cleaned. As the cleaning wheel 10 undergoes comparatively high velocity of rotation, the cleaning agents contained in the cloth 13 will adequately and positively clean and shine windows and other surfaces. The cleaning cloth 13 may be removed and a dry cloth applied to the

machine for finishing the work where it is desired to leave a high luster and polish on surfaces cleaned by this machine.

The invention is presented to fulfil the needs felt for a mechanically-driven window-cleaning machine, and its use will materially lessen the labor involved in this work.

Having thus described my invention, what I desire to secure by Letters Patent is:

- 10 1. The combination with a cleaning machine, of a socket member pivoted thereon, means on the socket member and means on the machine adapted to co-act therewith for locking the socket member in axial alignment or at right angles to the axis of the machine, a handle having one extremity arranged in the socket member for rotation, and means for tensioning the rotation of said handle in said socket member.
- 15 2. A cleaning machine comprising a cleaning wheel and a motor for driving the wheel, a handle, a socket member attached to the motor and adapted to rotatably receive one extremity of the handle, locking means pro-
- 20 vided respectively on the socket member and the motor for obtaining relatively fixed adjustments between the same, and a convolute spring attached respectively to the socket member and the handle to permit a limited elastic swiveling motion between the handle and the socket member, said spring also functioning to return the handle to normal position.
- 25 3. A cleaning machine comprising a cleaning wheel having a working face, a motor for driving the cleaning wheel, a handle pivotally attached to the motor, means coacting respectively with the motor and the handle to fix the handle and motor in relatively adjusted positions, means provided to allow limited rotation of the handle with respect to the motor and means provided for elastically restraining the aforesaid rotating movement of the handle, said means also serving to return the handle to a normal position.
